P. KAMINSKI

FIRE CONTROL ARRANGEMENT

Filed Aug. 25. 1921

Inventor:
Paul Kaminski
by *Magister*
his atys.

Patented July 1, 1924.

UNITED STATES PATENT OFFICE.

PAUL KAMINSKI, OF BERLIN-PANKOW, GERMANY, ASSIGNOR TO SIEMENS & HALSEY,
AKTIENGESELLSCHAFT, OF SIEMENSSTADT, NEAR BERLIN, GERMANY, A COR-
PORATION OF GERMANY.

FIRE-CONTROL ARRANGEMENT.

Continuation of application Serial No. 643,274, filed June 4, 1923. This application filed October 27, 1923.
Serial No. 671,103.

To all whom it may concern:

Be it known that I, PAUL KAMINSKI, a citizen of the German Empire, residing at Berlin-Pankow, Germany, have invented certain new and useful Improvements in Fire-Control Arrangements (for which I have filed applications: Germany, 19. 3. 17, No. S. 46447 XI/72 f; Sweden, 14. 6. 20, Nr. 2605/20; Norway, 19. 6. 20, No. 20594; Italy, 22. 6. 20, No. 38992; Spain, 6. 7. 20, No. 74507; Japan, 9. 7. 20, No. 38492; Denmark, 17. 7. 21, Ser. No. 2221-20; Holland, 28. 7. 20, Ser. No. 15845; Argentina, June 2, 1921, Ser. No. 23047), of which the following is a specification.

My invention relates in general to fire control arrangements and more particularly to arrangements or apparatus for allowing for the delay in discharging, i. e. the delay that ensues between the moment a gun aimed at the target is let off and the moment the projectile emerges from the muzzle.

There are two proper moments for firing guns mounted on moving bases, such as ships, and controlled from a central position or station. These two moments are:

1. In the case of guns fixed to the moving bottom, the moment in which the target passes through the sight line, and
2. In the case of guns trained so as to follow the target, the moment in which the target, that appears to be moving up and down past a middle position, reverses its direction of travel and is therefore at rest relatively to the gun.

In the former of these two cases the delay in discharging, i. e. the time that passes from the moment the sight line is on the target to the moment in which the projectile leaves the muzzle of the gun, must of course be allowed for. This allowance for the delay in discharging hitherto involved, in the said former cases of fixed guns, cumbersome special contrivances, which might generally be dispensed with in guns trained so as to follow the target, because in this latter case the effect of the delay in firing will generally be negligible, on account of the apparent motion of the target being very small in the neighbourhood of the position of the reversal of this motion, and as the position of rest occupied at

the point of reversal will always last a certain time.

But when the movements of the bottom carrying the gun are considerable, as in cases in which the ship rolls severely, it is extremely difficult to let off the guns at the moment of the reversal of its rolling motion, i. e., at the moment the ship is at rest. The operations of switching the controlling gear of gun-elevating machines on and off, and the continued motion of these machines after they are switched off, always cause a certain delay in the coming to rest of the gun. Hence, between the moment at which the position of reversal of the ship is recognized, and the moment at which the surely aimed projectile is discharged from the gun which has come to rest, there will always be a certain difference in time. It is therefore practically impossible to discharge the gun just at the moment of reversal, and the discharge will generally take place a short time after that moment. It is thus seen that a delay in discharging must also be reckoned with in the second of the above-mentioned cases.

The object of my invention is to eliminate the effect of the delay in discharge in such cases irrespective of the amount of rolling of the vessel. This is accomplished by inserting correcting devices between the sighting device (observation telescope) and the electrical signal transmitter which either directly controls the elevating machinery of the guns or enables the guns to be trained by the "follow the pointer" system. The said correcting devices are adapted to automatically eliminate the effect of the said delay in discharging.

The invention is illustrated in the drawing which is a diagrammatic perspective representation of a constructional form of the same.

The transmitter G which affects the elevation of the guns, and which is set by the apparatus (not shown) that imparts the ballistic elevation to them, is also set through the medium of the gear wheels J, H, by the handle, hand wheel or coupling K mounted on the shaft C. These setting movements correspond to the apparent motions of the target on account of the pivoted mirror F arranged before the sighting telescope, or the sighting telescope itself, being

constantly turned onto the target by corresponding motions being imparted to it by the handle K through the medium of the shaft C, the bevel wheel D, planet wheel R, 5 shaft A, worm S and the wormwheel S'. By this means the setting of the gun, or, in the arrangement illustrated, the setting of the transmitter, is effected in accordance with the rolling of the ship.

- 10 Now in order to allow for the delay in discharging, an additional movement is imparted to the gun or transmitter G. This additional movement is derived from a cam disk M whose curvature corresponds to the 15 delays of discharging that take place at all angles of lurch that the ship is liable to describe.

As the delay in discharging is generally an almost constant value, the correct shape 20 of the curve of the cam can easily be calculated, because the polar coordinates of this curve are defined by the particular angle of lurch in question, being the product of the delay in discharging (which may be assumed to be constant) and the angular velocity of the ship depending upon the value 25 of the particular angle of lurch. In practice the value of the angle of velocity of a rolling ship rises from zero at the moment 30 of reversal to a maximum when the deck is in horizontal position, which value is numerically equal to one half the value of the particular angle of lurch.

In the example illustrated in the drawing, when the mirror F or the sighting telescope is directed in aiming, a rotary motion corresponding to the particular rolling motion in question, is imparted to the cam M when the shaft C is turned by 35 the handle K, the said motion being transmitted through the gear-wheels H, L, P, T, U and V. This motion is transmitted against the action of a spring B to the rack N from which it is transmitted further through the pinion O to the bevel 40 wheel Q of the planet gear D R Q. The wheel R thus receives an additional motion to compensate for the delay in discharging at any angle of lurch, this additional motion being imparted to the shaft A and 45 through this shaft to the mirror F of the aiming telescope. Therefore the additional correction corresponding to the delay in discharging is effected between the transmitter 50 G, which may comprise any known type, for example such as is disclosed in the U. S. Patent No. 1,122,942 granted to me on December 29th, 1914, that influences the inclination of the cannon and the mirror F or the aiming telescope itself, and as the 55 mirror or the telescope is kept directed to-

wards the target the inclination of the guns will be altered by the desired amount.

The effect of any heel or list of the vessel that may occur may be compensated 65 for by adjusting the cam M in accordance with the said heel by means of a gear X Y. The adjustment may be effected with the aid of a pointer Z turned before a dial. By this means the delay in discharging, which 70 has been determined once and for all, is corrected in its effect in accordance with the particular angle of heel.

I claim:

1. In an electrical system for the tele- 75 control of guns in combination a transmitter for effecting the inclination of the guns, a sighting device, means actuated by the operator for inclining the sighting device in accordance with the direction of the target and for simultaneously setting said transmitter, and additional means mechanically driven by said setting means for automatically imparting a correctional movement to said sighting device corresponding 80 to the delay in gun discharging and the angular velocity of the ship's heeling.

2. In an electrical system for the tele- 85 control of guns, a transmitter for effecting the inclination of the guns, a sighting de- 90 vice, means actuated by the operator for inclining the sighting device in accordance with the direction of the target and for simultaneously setting said transmitter, a cam whose curvature is a product of the 95 delay in discharging the guns, and the angular velocity of the ship's rolling, means mechanically connected to said operator actuated means for rotating said cam, a rack adapted to be displaced by said cam and 100 to impart additional movement to said sighting device.

3. In an electrical system for the tele- 105 control of guns, a transmitter for effecting the inclination of the guns, a sighting de- 110 vice, means actuated by the operator for inclining the sighting device in accordance with the direction of the target and for simultaneously setting said transmitter, a cam whose curvature is a product of the 110 delay in discharging the guns and the angular velocity of the ship's rolling, means mechanically connected to said operator actuated means for rotating said cam, a rack adapted to be displaced by said cam and to 115 impart additional movement to said sighting device, and adjusting means for the cam so as to compensate for errors due to the rolling of the ship.

In testimony whereof I affix my signature.

PAUL KAMINSKI.

Certificate of Correction.

It is hereby certified that in Letters Patent No. 1,499,664, granted July 1, 1924, upon the application of Paul Kaminski, of Berlin-Pankow, Germany, for an improvement in "Fire-Control Arrangements," an error appears requiring correction as follows: In the heading to the printed specification, lines 5 and 6, strike out "Continuation of application Serial No. 643,274, filed June 4, 1923. This application filed October 27, 1923. Serial No. 671,103." and insert *Application filed August 25, 1923. Serial No. 495,291.*; and that the said Letters Patent should be read with this correction therein that the same may conform to the record of the case in the Patent Office.

Signed and sealed this 19th day of August, A. D. 1924.

[SEAL.]

KARL FENNING,
Acting Commissioner of Patents.
